DESCRIPTION

FIG. 1 is a front elevation view of a flask with cap according to the present invention;

FIG. 2 is a left side elevation view of the flask with cap of FIG. 1;

FIG. 3 is a back elevation view of the flask with cap of FIG. 1; FIG. 4 is a top elevation view of the flask with cap of FIG. 1; FIG. 5 is a bottom view elevation of the flask with cap of FIG. 1;

FIG. 6 is a front elevation view of the flask with cap of FIG. 1, showing the flask in isolation without the cap;

FIG. 7 is a left side elevation view of the flask with cap of FIG. 1, showing the flask in isolation without the cap;

FIG. 8 is a back elevation view of the flask with cap of FIG. 1, showing the flask in isolation without the cap;

FIG. 9 is a top elevation view of the flask with cap of FIG. 1, showing the flask in isolation without the cap;

FIG. 10 is a bottom view elevation of the flask with cap of FIG. 1, showing the flask in isolation without the cap

FIG. 11 is a front elevation view of the flask with cap of FIG. 1, showing the cap in isolation without the flask;

FIG. 12 is a left side elevation view of the flask with cap of FIG. 1, showing the cap in isolation without the flask;

FIG. 13 is a back elevation view of the flask with cap of FIG. 1, showing the cap in isolation without the flask;

FIG. 14 is a top elevation view of the flask with cap of FIG. 1, showing the cap in isolation without the flask;

FIG. 15 is a perspective view elevation from the bottom of the flask with cap of FIG. 1, showing the cap in isolation without the flask;

FIG. 16 is a perspective view elevation from the top of the flask with cap of FIG. 1, showing the cap in isolation without the flask; and,

FIG. 17 is a perspective view elevation thereof, showing the flask with cap in an assembled manner.

The broken lines depict environment only. The broken lines depict portions of the flask with cap that form no part of the claimed design.
